Primary Examiner — Cynthia M. Chin(74) Attorney, Agent, or Firm — Thomas Y. Kendrick; Benamen E. Kern; Kern Kendrick LLCCLAIM

The ornamental design for a tent, as shown and described.

DESCRIPTION

FIG. 1 is a front perspective view of a tent;
FIG. 2 is a front elevation view thereof;
FIG. 3 is a rear perspective view thereof; and,
FIG. 4 is a top plan view thereof.

In FIG. 4, the shape of the base of the tent is shown in broken lines for illustrative purposes only and forms no part of the claimed design.
